Primary Examiner — Manpreet Matharu*Assistant Examiner* — Suzanne Tisdell(74) Attorney, Agent, or Firm — MU Patents; Timothy Marc Shropshire; Garrett James O’Sullivan(57) CLAIM

The ornamental design for a tactical battery, as shown and described.

DESCRIPTION

FIG. 1 is a rear perspective view of a tactical battery showing our new design;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines depict environmental subject matter that is not included in the claim.

1 Claim, 8 Drawing Sheets(56)
